UNITED STATES PATENT OFFICE.

NEWTON W. BUCH, OF NEW CASTLE, PENNSYLVANIA, ASSIGNOR TO SAFETY ARMORITE CONDUIT COMPANY, OF PITTSBURGH, PENNSYLVANIA, A CORPORATION OF PENNSYLVANIA.

METHOD OF GALVANIZING.

1,141,931.

Specification of Letters Patent.

Patented June 8, 1915.

Original application filed June 28, 1913, Serial No. 776,430. Divided and this application filed October 20, 1914. Serial No. 867,577.

To all whom it may concern:

Be it known that I, NEWTON W. BUCH, a citizen of the United States, residing at New Castle, in the county of Lawrence and State 5 of Pennsylvania, have invented a new and useful Method of Galvanizing, of which the following is a full, clear, and exact description, reference being had to the accompanying drawings, forming part of this specification, in which—

Figure 1 is a longitudinal section through one form of apparatus for carrying out my novel method. Fig. 2 is a plan view. Fig. 3 is an end view of one of the pipe supporting members on a larger scale, and Fig. 4 is a sectional view on the line IV—IV of Fig. 3.

My invention relates to the galvanizing of pipes, bars, etc., and is designed to provide 20 a method of novel character by means of which the work of galvanizing may be rapidly and thoroughly performed.

The precise nature of my invention will be best understood by reference to the accompanying drawings, which will now be described, it being premised, however, that various changes may be made without departing from the spirit and scope of my invention, as defined in the appended claims.

30 In the drawings, the numeral 2 designates a tank for containing the acid bath 3.

4 designates a skid leading into the bath on which the pipes to be galvanized are fed in any desired manner. Rotatably mounted 35 in the bearings connected to the tank 2 are shafts 5—5 having connected thereto sprocket wheels 6 for an endless conveyer 7. This endless conveyer is provided with hooks 8 which are arranged to lift the pipes or 40 rods from the skid 4 and convey them to an inclined skid 9. This skid 9 extends from the acid tank 2 to a point adjacent to a hot metal tank 10, having a furnace 11 for keeping the metal in a molten condition.

45 12 is a step on the skid 9 which is arranged to prevent the pipes or rods rolling down the skid to the hot metal tank 10.

Extending beyond the hot metal tank 10 is a third skid 13, over which the pipes are 50 moved after they have been galvanized, and 14 is an endless conveyer above the hot metal tank 10 which is arranged to draw the pipes

or rods through the molten metal tank. This endless conveyer is mounted on sprocket wheels 15 connected to shafts 16 55 which may be rotated in any desired manner, and extending outwardly from both of the chains of the conveyer are projections 17 for engaging the hooked portions 18 on pipe supporting members 19. These pipe 60 supporting members are provided with laterally extending bosses 20 which are screw threaded to receive the ends of the pipes or rods, and are each provided with an opening extending from the upper end thereof into 65 the tapped recess.

Mounted within the hot metal tank 10 are guides 21. The pipes or rods are fed into the tank 2 over the skid 4 in which they are treated by means of the acid to remove 70 grease, etc. in order to prepare them for the galvanizing bath. The pipes are conveyed successively from the tank 2 to the skid 9 and pass by gravity down the skid 9 to the stop 12. The pipes are then moved successively beyond the stop 12 and a supporting member 19 is connected to each end thereof. It is then passed to a point above a plurality of burners or hot plates 22, which are arranged to heat the pipes to drive off some of 80 the moisture from the acid bath. The supporting members 19 are then elevated at their outer ends by means of a lever such as shown at 23 so that the hooked members thereof will be engaged by the projections 85 17 on the conveyer 14. The forward movement of the conveyer will carry the pipe into the hot bath in the tank 10 and the guides 21 will hold the pipe down below the upper surface of the molten metal. During the 90 passage of the pipe through the molten metal, the outer surface thereof will be galvanized and any vapor caused by the moisture within the pipe will pass out through the openings in the connecting members. 95 After the pipe has been drawn through the hot metal bath it will be raised onto the skid 13 and disconnected from the supporting members and the conveyer.

The advantages of my invention will be 100 apparent to those skilled in the art, since it provides an extremely efficient and rapid method of galvanizing pipe. The apparatus also overcomes the difficulties which have

heretofore been experienced due to the rapid vaporization within the pipe of any moisture such as remains from the acid bath, as the vapor can pass off through the openings in the supporting members.

5 A further advantage consists in the fact that the threaded ends of the pipe are protected against being coated and that no galvanizing material can enter the interior of the pipes during the galvanizing operation.

10 While I have shown my invention as being carried out in connection with hot galvanizing, it will be readily understood that my improved method is also applicable to electrolytic galvanizing, the pipes being supported and moved through the electrolyte in a manner similar to that of hot galvanizing.

15 This application is a division of my pending application Serial No. 776,430, filed June 20, 1913.

20 I claim:—

1. The herein described method of coating pipes, which consists in applying closures to the ends of the pipe to be coated, at least one of said closures having a vent opening, 25 and then moving the pipe through a heated coating bath while maintaining said vent

opening above the level of the coating material in the bath, substantially as described.

2. The herein described method of coating pipes having threaded end portions, which consists in applying removable vented closures to the ends of the pipe of a character to cover the threads thereof, and moving the pipe through a heated coating bath while maintaining the vent openings of said closures above the level of the coating material in the bath, substantially as described.

3. The herein described method of coating pipes, which consists in applying closures to the ends of the pipe to be coated, at least one of said closures having a vent opening, and then moving the pipe through a heated coating bath by engagement with said closures while maintaining said vent opening above the level of the coating material in the bath, substantially as described.

In testimony whereof, I have hereunto set my hand.

NEWTON W. BUCH.
